UNITED STATES PATENT OFFICE

KARL WITZELL, OF BERLIN-LICHTERFELDE, GERMANY, ASSIGNOR TO RHEINISCHE METALLWAAREN- UND MASCHINENFABRIK, OF DUSSELDORF-DERENDORF, GERMANY, A CORPORATION OF GERMANY

BARREL OF FIREARMS

Application filed November 18, 1929, Serial No. 408,059, and in Germany June 1, 1928.

The life of the barrels of fire arms is only limited as, during firing, burning out particularly of the loading compartment and the adjoining portions of the barrel grooves or furrows occurs. To make use of the portion of the barrel still fit for service, it is customary to replace the burnt out part of the barrel only by an insertion piece. When using this method it is, however, absolutely necessary that the insertion piece jointless connects to the barrel and it is particularly required that all grooves or furrows of the inserted new piece stepless merge into the inside of the barrel. To obtain this, means must be provided by which the new piece inserted into the barrel can easily be brought in the proper angular position and may then be fixed in this position, so that it is absolutely prevented from moving during firing and turning under the influence of the grooves or furrows. The insertion piece must also be easily replaceable or exchangeable.

According to the present invention these objects are obtained by the fact that the insertion piece, snugly fitting the correspondingly bored barrel, carries at its front face one or more projections which engage correspondingly shaped openings provided in the adjoining front face of the barrel. Preferably the adjoining faces of the insertion piece and of the barrel are formed as helicoidal surfaces of equal pitch the direction of which is opposite to that of the grooves or furrows of the barrel. Each of the helicoidal surfaces is provided with a stepped face or shoulder extending in the direction of the axis of the bore. The helicoidal surfaces are easy to make and the stepped face or shoulder of the insertion piece may, without any difficulty, be arranged in such a position that, when it is brought into contact with the counter-face of the barrel, the grooves or furrows of the insertion piece

smoothly and stepless merge into the grooves or furrows of the barrel.

In the accompanying drawing a longitudinal section of one construction according to the invention is shown by way of example in connection with a barrel having an inserted bored piece and an insertion cartridge magazine.

In the bored out hind portion of the barrel *b* a spare tube or insertion piece *a* is fitted which contains the loading chamber and a portion of the grooves or furrows. The adjoining faces of the barrel *b* and of the insertion piece *a* are formed as single helicoidal surfaces *d* of equal flat pitch the direction of which is opposite to that of the grooves or furrows. The shoulders or stepped faces *c* of the helicoidal surfaces are of the same direction as the axis of the bore and occupy such a position at both parts that, when the shoulders engage each other, the grooves or furrows of both parts exactly fit or merge into each other. During firing, the forward movement of the projectile causes the helicoidal surface *d* of the insertion piece *a* to be firmly pressed against the helicoidal surface of the barrel. Moreover the torque caused by the grooves or furrows and acting upon the insertion piece *a* is transferred to the barrel *b* by means of the stepped faces *d* or shoulders *c* without any possibility of relative rotation or displacement of the two tube-like parts *a* and *b*. If it is desired to remove the insertion piece *a*, it is, for the purpose of loosening, first turned with regard to the barrel *b* in the direction of the grooves or furrows, whereupon the helicoidal surfaces *d* disengage the two parts, so that the insertion piece *a* may easily be pulled out to the rear of the barrel.

What I claim is:

In a barrel of fire arms provided with grooves or furrows and an exchangeable insertion piece, in combination a projection at the front face of said insertion piece and a

corresponding opening in the rear face of said barrel adjoining the front face of said insertion piece, said adjoining front faces of said insertion piece and said barrel being 5 formed as helicoidal surfaces of equal pitch the direction of which is opposite to that of said grooves or furrows and being each provided with a stepped face or shoulder extending in the direction of the axis of said barrel.

10 In testimony whereof I have affixed my signature.

KARL WITZELL.
